TOASTER HANDLE

Philip E. Willman, St. Charles Township, Kane County, Ill., assignor to McGraw Electric Company, Elgin, Ill., a corporation of Delaware

Application May 5, 1952, Serial No. 19,585

Term of patent 14 years

(Cl. D81—10)

To all whom it may concern:

Be it known, that I, Philip E. Willman, a citizen of the United States, residing in St. Charles Township, county of Kane, and State of Illinois, have invented a new, original, and ornamental Design for a Toaster Handle, of which the following is a specification, reference being had to the accompanying drawings, forming a part thereof, in which

Fig. 1 is a view in side elevation of a toaster handle embodying my new design;

Fig. 2 is a perspective view of the toaster handle as seen from below;

Fig. 3 is a top plan view thereof;

Fig. 4 is an end elevational view thereof; and

Fig. 5 is a perspective view showing the toaster handle as seen from above.

I claim:

The ornamental design for a toaster handle, substantially as shown.

PHILIP E. WILLMAN.
